P. A. UDALL

CARRIER TUBE

Original Filed Dec. 24, 1923

UNITED STATES PATENT OFFICE.

PHILLIP A. UDALL, OF NEW YORK, N. Y., ASSIGNOR TO G. & G. ATLAS SYSTEMS, INC.,
A CORPORATION OF NEW YORK.

CARRIER TUBE.

Application filed December 24, 1923, Serial No. 622,402. Renewed September 19, 1925.

To all whom it may concern:

Be it known that I, PHILLIP A. UDALL, a citizen of the United States, residing at New York city, in the county of New York and State of New York, have invented certain new and useful Improvements in Carrier Tubes, of which the following is a specification.

My invention relates to a new and improved carrier tube.

One of the objects of my invention is to make a new and improved carrier tube which will be especially suitable for use in pneumatic carrying devices.

Another object of my invention is to devise a new and improved carrier tube having a metal shank or body and heads made of rubber or any other resilient material.

Another object of my invention is to provide a new and improved method of making an article of this character.

Another object of my invention is to provide a method of making an article of this character and a new and improved method of making this article whereby the metal shank and the resilient heads can be readily connected in a firm and reliable manner and can also be readily disconnected.

Other objects of my invention will be set forth in the following description and drawings.

Fig. 1 is an elevation partially in section and showing one of the forms of apparatus which can be used for carrying out my method.

Fig. 2 is a sectional view partially in elevation and showing in greater detail some of the parts illustrated in Fig. 1.

Fig. 3 is an elevation partially in section and shows in detail some of the parts illustrated in Fig. 1. This figure is a section on the line 3—3 of Fig. 4.

Fig. 4 is a bottom view of Fig. 3.

Fig. 5 is a detail sectional view showing one step in the method of connecting the resilient head to the metal shank.

Fig. 6 is a top view of Fig. 5.

Fig. 7 is a section on the line 7—7 of Fig.

5. Fig. 8 is a top view of a device or tool used for separating the various parts of the device.

Figs. 9, and 10 and 12 show a tool which

can be used for detaching the head of the tube from the body thereof.

Fig. 11 shows how the tool shown in Fig. 12 is applied.

The carrier tube has a metal body, or shank 24 which is open at one side thereof so that the object to be conveyed can be readily placed within the tube. This metal shank or body is of the ordinary and well-known shape. The said shank 24 has a resilient heads 23 of larger diameter connected thereto. These heads are made of any suitable resilient material so as to have an airtight fit in the pneumatic tube. As clearly shown in Fig. 5, each head 23 has a recess having a retaining ring 30. This retaining ring 30 has a recess 31 having two rectangular portions in the body of said ring formed by a suitable stamping operation, as shown in Fig. 6. Hence as clearly shown in Figs. 2 and 3, the entire bottom of the ring 30 does not rest upon the adjacent part of the head 23 and the peripheral portion of the said ring 30 is spaced from the bottom of the respective recesses of the head to which it is to be connected. Each retaining ring 30 co-operates with an inner retaining ring 25 which fits against the adjacent end of the metal body 24, as shown in Fig. 7 each inner retaining ring 25 has two stamped out tongues of prongs 26 and 27 so that slots 28 and 29 are formed in each retaining ring 25. Each end of the body 24 has openings through which the prongs 26 and 27 can project and each head 23 has similar openings and corresponding openings are formed in the recessed part 31.

Hence, after each outer retaining ring 30 is pressed firmly in the direction of its adjacent inner ring 25 while it is prevented from turning and the ends of the prongs 26 and 27 are then bent down as illustrated in Fig. 2 while said ring 30 is prevented from turning, the said bent down ends are forced against the adjacent inner retaining ring 25 and the parts are very firmly held in position. Each prong then has a vertical portion and a horizontal bent-down portion, said bent down portion being in one of the rectangular portions of recess 31.

In order to make this article, the apparatus shown in Figs. 1, 2 and 3 may be used although my method can be practiced by

various forms of apparatus. A bracket 10 is connected to any convenient support and this has a solid projecting portion 10^a upon which the end of the body 24 is adapted to rest.

A lever 12 has a rod 11 pivoted thereto by means of a pin 13. The rod 11 has a recess at its lower end and the lower rod 14 is held in said recess by means of the pin 14'. A head 15 is slidably mounted at the bottom of the lower rod 14 and a compression spring 16 is mounted on the rod 14 between the bottom of the rod 11 and the top of the slidable head 15. The bottom portion of the lower rod 14 has a vertical groove 17 into which a screw 18 mounted upon the slidable head 15 fits, whereby proper guiding means are provided for the movement of the head 15. The head 15 has projections 21 and 22 at the bottom thereof as shown in Fig. 3 and Fig. 4.

As shown in Fig. 3, the bottom of the rod 14 has a small enlargement upon which the top of the slidable head 15 fits so as to limit the lower movement of the head 15 and prevent it from dropping off the rod 14. The bottom of the rod 14 has projections 19 and 20 as shown in Fig. 3 and Fig. 4.

When the parts are to be assembled, the operator actuates the lever 12 with one hand and with the other hand he turns the shank or shell 24 together with the parts above it until he feels that the projections 21 and 22 of the head 15 have entered or become located within the rectangular portions of the recess 31 of the outer retaining ring 30. These projections 21 and 22 then fit snugly within the angular portions of the said recess 31 so as to prevent the outer ring from turning while the ends of the prongs 26 and 27 are being bent downwardly in opposite directions. Without this part of the device the bending down of the ends of said prongs 26 and 27 would cause the outer ring 30 to turn so that the prongs 26 and 27 would be bent or twisted out of the desired shape and this would make it almost impossible to separate the parts again.

After the operator has properly located the projections 21 and 22 within the angular portion of the recess 31 so that they are directly adjacent the ends of the prongs 26 and 27, he then presses down more firmly upon the lever 12. The further downward movement of the lever 12 forces the rods 11 and 14 downwardly so as to compress the spring 16. This produces a compression of the resilient material of the head 23 while the final operations are performed for assembling the parts. The projections 19 and 20 of the rod 14 then contact with the

ends of the prongs 26 and 27 so as to bend them down at right angles to the upstanding parts of the said prongs. 65

The resulting device is free from screws and objectionable projecting parts within the body 24 as the inner rings 25 present a substantially smooth surface so that paper objects can be easily placed within the completed article and can be easily taken out without any tearing or jamming. 70

In using these devices it is important to be able to readily remove the resilient heads 23 and replace them by new heads because there is considerable wear upon these resilient heads due to the fact that they must fit closely within the pneumatic tubes and must move with considerable velocity within these tubes. 75

The improved construction above mentioned which employs a minimum number of parts enables the separation with great 85 facility.

I provide an additional tool or device 32, illustrated in Fig. 8, to facilitate the separation of the parts. This device 32 consists substantially of a washer having two downwardly bent prongs 33 and two upward lugs or teeth 34. The washer 32 is adapted to fit upon the finger 10^a and the prongs 33 fit within recesses 10^b of the finger 10^a so that the washer 32 is prevented from turning. 90

When the tube to be separated is then placed upon the finger 10^a as illustrated in Fig. 1, for example, the teeth 34 fit within the slots 28 and 29 of the inner retaining ring 25 so that the tube cannot turn, whereas when the parts were assembled it could be freely turned by the hand of the operator because the washer 32 was not used during the assembling operation. 100

A tool of the type shown in Figs. 9, 10, and 12 is now employed to upwardly bend the bent down ends of the prongs 26 and 27. 105

The rod 11 can be removed from the device shown in Fig. 1 by removing the detachable pin 10' and sliding out the parts connected to the rod 11 upwardly through the guide 11'. 110

The shank 35 of the separating tool can now be fitted through the guide 11' and this separating tool can then be turned by the angle bar 36 which has a downwardly bent part 36' which limits the turning of the tool 35 by contacting with the member 10. With the tube in the position shown in Fig. 1, the tool 35 is now moved downwardly until the teeth 37 are directly behind the bent down ends of the prongs 26 and 27. These teeth 37 enter the recess 31 so as to directly act upon the bent down ends of the prongs 26 and 27. When the tool 35 is turned the ends of the prongs 115

26 and 27 are straightened because the tube cannot revolve due to the use of the washer 32.

It is therefore possible to separate the 5 parts of a tube in a very short time and with the use of substantially the same mechanism that was employed for the original assembling of the parts.

It is clear that my device is made of a 10 minimum number of parts and that a minimum number of operations and a minimum of time are required to make it or separate it.

15 I have shown preferred embodiment of my invention, but it is clear that numerous changes and omissions could be made without departing from its spirit.

Thus it would be possible to form the top 20 of body portion 24 with prongs such as are here illustrated in connection with inner retaining ring 25. In either construction, the fastening means for securing the resilient

head to the body portion would be free from any projecting parts within the said body portion.

25

I claim:

1. A method connecting a resilient head portion provided with a recess having a rigid outer retaining ring located therein, to the body portion of a pneumatic carrier 30 having an inner retaining ring at the end thereof, which consists in forcing the said outer rings towards the said inner ring and then securing said outer ring in position while the resilient material of the head remains compressed.

2. A method according to claim 1 in which the outer ring is prevented from revolving while the said outer ring is forced 35 in a direction towards said inner ring.

40 In testimony whereof I hereunto affix my signature.

PHILLIP A. UDALL.
